ADJUSTABLE ORIFICE GAS-AIR MIXER
NOZZLE

Edward Gordon Murray, Denver, Colo.

Application July 16, 1951, Serial No. 236,992

3 Claims. (Cl. 158—118)

1

This invention relates to a gas orifice nozzle for gas burners, and has for its principal object the provision of an orifice nozzle which will produce a more efficient fuel mixture than the present types of fixed orifice nozzles.

Another object of the invention is to provide means for controlling the size and position of the orifice so that the flow of gas therethrough may be regulated to provide the most efficient gas and air mixture under all pressure conditions.

A further object is to incorporate an enlarged swirl chamber in a gas orifice nozzle which will create a palpitating vibration to the jet of gas for efficient entrapment and intermixture of the air therewith.

A still further object is to so construct the orifice member that it can be placed in position on jet bushings without requiring any change in the burner structure.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a fragmentary, longitudinal section through a conventional burner fuel mixer, illustrating the invention in place therein;

Fig. 2 is an enlarged, longitudinal section through the improved gas orifice nozzle; and

Fig. 3 is a still further enlarged front view thereof.

In Fig. 2 the orifice of the nozzle is illustrated in its fully open or aligned position, and in Fig. 3 the orifice is illustrated in the position of greatest mis-alignment.

In Fig. 1, parts of a conventional gas fuel mixing system are indicated by numeral as follows: gas main 10, mixing tube 11, air ports 12, orifice sleeve 13, and gas supply nipple 14. The improved orifice nozzle is designed to fit into the orifice sleeve 13, and to be threaded onto the supply nipple 14.

The improved gas orifice nozzle consists of a tubular barrel 15 having a closed front head 18 and an open rear end provided with internal threads 17 for receiving the threaded nipple 14. The barrel is preferably provided with suitable wrench-engaging faces 16 to facilitate threading it onto the nipple 14. The closed head 18 of

2

the barrel 15 is reduced in diameter and externally threaded, as indicated at 19, to receive an internally threaded, cup-like cap 20 corresponding in diameter to the barrel. The cap stops against a stop shoulder 21 on the barrel 15, and when threaded tightly against this shoulder, the cap will be spaced from the head 18 to provide a thin, flat, circular swirl chamber 22 between the cap and the head.

10 The barrel head 18 is provided with an inner gas orifice 23, and the cap 20 is provided with a similar outer gas orifice 24. The two orifices are drilled simultaneously when the cap is tight against its shoulder 21 so that they will align with each other, as shown in Fig. 2. The aligned orifices 23 and 24 are positioned eccentrically of the common axis of the barrel and cap, the amount of eccentricity being slightly less than the diameter of the orifice. Thus, when the cap is rotated 180° from the position of Fig. 2, to the position of Fig. 3, the outer orifices 24 will but slightly overlap the inner orifice 23.

When in place, the outer orifice 24 projects a jet of gas into the mixer tube 11. The characteristics of this jet can be regulated and controlled by rotation of the cap 20 to various relative positions between the inner and outer orifices 23 and 24. In the majority of installations, the cap will be threaded tightly against its shoulder 21 so that the two orifices will align with each other at this point eccentric of the axis of the barrel 15. This causes a high-frequency vibrating or pulsating, swirling action in the gas jet which efficiently and effectively mixes and entraps air into the gas stream.

35 The exact reason for this unique action on the gas stream is not definitely known, but it has been found that if the cap 20 tightly engages the head 18, the action disappears. Therefore, it must be due to the action of the flat, circular, open swirl chamber 22, which apparently causes the gas to swirl intermittently into the outer jet opening 24, causing a vibrating interruption in the flow of gas at a high frequency. The action and characteristics of the jet and the mixture with the air can be regulated by rotation of the cap 20 to provide greater or less interference between the orifices, and to vary the capacity of the swirl chamber 22.

50 The air shutters usually provided on the air ports 12 may be entirely eliminated with the use of this improved jet nozzle, since perfect control of the gas and air mixture may be had by proper regulation and setting of the position of the cap 20.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A gas jet orifice nozzle comprising: a tubular barrel having an open rear end provided with internal threads; a closed front head formed on said barrel; a cup-like cap rotatably mounted on said head; a closed bottom in said cap; means permanently spacing said bottom from said head to form a flat, circular, inner chamber in a plane at right angles to the axis of said barrel; a first gas orifice in said head; and a second similar orifice in said bottom, the axes of both of said orifices being eccentric of the axis of said head and cap, and the latter axis passing through both said orifices at all rotative positions of said cap.

2. A gas jet orifice nozzle as described in claim 1 in which the closed front head is of lesser diameter than said tubular barrel, and having an annular shoulder surrounding said head between said head and said barrel, said shoulder being positioned to be abutted by the sides of said cap and acting to prevent the bottom of said cap

from contacting said head so as to maintain the orifice in said head fully open at all rotative positions of said cap.

3. A gas jet orifice nozzle as described in claim 2 in which the cap is threaded onto the head and in which the threads and the orifices in said head and in the bottom of said cap are relatively related so that when said cap is threaded inwardly toward said head to its maximum inward position, the bottom of said cap will be spaced from said head a minimum distance, and the orifice in said head will be in axial alignment with the orifice in said bottom, and when said cap is threaded outwardly to increase the spacing between said head and the bottom of said cap, said orifices will move out of axial alignment with each other but will always remain in overlapping relation with each other.
